CLAIM

The ornamental design for a veterinary otoscopic tip element, as shown and described.

DESCRIPTION

FIG. 1 is a first view of an embodiment of the design.

FIG. 2 is a view that is substantially opposite to the first view of FIG. 1.

FIG. 3 is a second view of an embodiment as it is attached to an otoscope.

FIG. 4 is a view that is substantially opposite to the second view of FIG. 3.

FIG. 5 is a top perspective view of the embodiment that is shown in FIG. 3.

FIG. 6 is a front perspective view of the embodiment that is shown in FIG. 3; and,

FIG. 7 illustrates use of a side port (notch) of the embodiment that is shown in FIG. 3.

The otoscopes and curettes are shown for illustrative purposes only and form no part of the claimed design.
